UNITED STATES PATENT OFFICE.

MIKE KAMENOS, OF WASHINGTON, DISTRICT OF COLUMBIA.

WEARING-APPAREL FOR DIVING AND SWIMMING.

1,369,669.

Specification of Letters Patent. Patented Feb. 22, 1921.

Application filed July 8, 1920. Serial No. 394,790.

To all whom it may concern:

Be it known that I, MIKE KAMENOS, a citizen of the United States, residing at Washington, in the District of Columbia, 5 have invented certain new and useful Improvements in Wearing-Apparel for Diving and Swimming, of which the following is a specification.

This invention relates to the class of life 10 preservers, and pertains especially to an apparatus for suspending a human body under water and permitting diving, swimming, and other desired action of the body in submerged position.

15 The object of the invention is to provide a novel and peculiar diver's and swimmer's appliance or suit which shall fit and inclose the whole figure or human body in airtight and water-tight condition, and having 20 means for supplying air, drinking water and food during the wearing of the appliance for diver's use and for submerged swimming, and other submarine purposes whereby the wearer may remain submerged 25 an unusual period of time in active normal condition.

A further object of the invention is to provide a submarine wearing apparel or suit of such novel and peculiar construction and 30 combination of parts as to afford the wearer diving, swimming and various other movements of the body under water, and to furnish a combination of rubber and cork in such manner as to facilitate said movements.

35 Various other objects, advantages and improved results are attainable in the practical application of the invention.

In the accompanying drawings forming part of this application:—

40 Figure 1 is a perspective view showing the application of the invention.

Fig. 2 is a vertical sectional view.

Fig. 3 is a cross section taken on the dotted line 3—3 Fig. 1.

45 Fig. 4 is a cross section taken on the dotted line 4—4 Fig. 1.

Fig. 5 is a cross section taken on the dotted line 5—5 Fig. 1.

50 Fig. 6 is a detail sectional view of one of the pipe couplings.

Fig. 7 is a detail perspective view of part of a closing joint.

The same reference characters denote the 55 same parts throughout the several views of the drawings.

In carrying out my invention, I employ preferably a body suit composed of rubber, and comprising a body member 1, having fingered sleeves 2, legs 3, and shoes 4. The back of the body member is extended to 60 form a head-inclosing member 5 having a vision glass 6, and said member 5 has a depending neck and chest member 7, joined with the front upper portion of the body member 1, as will be hereinafter explained. 65

The front of the body portion 1 is separated vertically so as to permit access of the body, arms, legs and feet, and the meeting edges of the said separated rubber portion are each provided with metal strips 8 70 having the rubber folded and secured around them so as to form a closed joint when secured together, as by thumb screws 9. The same metal strip fastening is used for closing the joint between the breast 75 member and the upper portion of the body member as shown at 10 in Figs. 1 and 2. In order to vary the size of the body member as desired or as occasion may demand, I employ strap and buckle attachment 11. 80 The ankle portion of the legs is provided with straps 12 having a cork fin 13 to assist in swimming operations.

In order to overcome in part the weight of the body in submerged position, and for 85 other purposes hereinafter appearing, I secure on each of the sides of the body member 1, a cork fin 14 of peculiar shape as shown in the drawings, for facilitating diving and swimming. One of the fins 14 has a 90 chamber 15 for storing drinking water supplied through the screw plug 16, and the other fin has a like chamber 17 for storing food. Obviously these cork fins are tightly secured to or joined with the body member 95 1, and have an outer casing or covering of rubber 18.

The head member 5 has a cork mounting 19 having an outer covering of rubber 20, and the cork is projected at each side of the 100 head to form fins 21 corresponding with the fins 14. The apex of the head cork has a pair of air pipes 22 extending therethrough into the head member 5, and said pipes are connected with air pipes 23 by means of 105 couplings 24, which permit vertical movement of the pipes 22 and 23. The pipes 23 are secured to and extend through a cork buoy or float 25, and project therefrom into a glass dome 26 having air apertures 27, for 110

supplying air to the head of the wearer of the appliance.

In order to supply the wearer with drinking water, the water chamber 15 has a pair 5 of water pipes 28 leading from within the chamber adjacent to the bottom and passing through the wall thereof and through the body member into the breast member, and said pipes are attached to a holder 29 10 having mouth nipples 30 to which said pipes are attached. The holder is free to be handled by the wearer as desired within the head and breast members.

Obviously the arms may be withdrawn 15 from the sleeves, without opening the appliance, so as to reach into the said chambers through the body member. The water plug may be operated for supplying water without removing the arms from the sleeves.

20 It will be understood that while the position float remains unchanged, the appliance enables the wearer to assume diving, swimming and various other positions, and to remain under water an unusual length of 25 time, and that the wearer may swim to the water surface as desired.

I do not wish to limit the invention as to material, shape and size, but reserve the right to make such changes and variations 30 in the manufacture and practical application of the invention as may come within the scope of the appended claims.

Having thus described my invention, what I claim as new and desire to secure by Letters Patent is:—

35 1. In wearing apparel for submarine use,

a rubber suit enveloping the whole body to the exclusion of air and water, a fin on each side of the suit and each fin having a chamber therein means for supplying water to 40 one of the chambers, interior water pipes leading from the water chamber into the head of the suit, and mouth nipples on the head end of said pipes.

2. In an appliance of the character described, 45 a waterproof suit for enveloping the whole human body, exterior projections fixed to the sides of the suit and forming, respectively, a water container and a food container, corresponding projections fixed 50 to the head member of the suit and spaced apart from said side projections, and leg fins corresponding with the said side and head projections.

3. In an appliance of the character described, 55 the combination of a float having an air chamber projecting therefrom and provided with air ducts, air pipes extending from said chamber through the float, a waterproof suit having a cork covering 60 forming fins, air pipes extending through the top covering into the head of the suit, and couplings for said float and head pipes permitting vertical movement of the float with respect to the suit.

65 In witness whereof I hereunto set my hand in the presence of two witnesses.

MIKE KAMENOS.
